RAILWAY CAR

Sigvald F. Udstad, Berwick, Pa., assignor to
American Car and Foundry Company, New
York, N. Y., a corporation of New Jersey

Application April 30, 1938, Serial No. 205,377

19 Claims. (Cl. 105—427)

This invention relates to railway cars in general and in particular to railway cars of the streamlined type wherein the step wells are closed by movable skirting. Previous constructions using folding steps and movable skirting have required the carrying of the load past the step well necessitating very heavy reinforcements to transmit the side wall loads to the center sill at the step well which resulted in a much heavier car than otherwise required.

It is an object, therefore, of the present invention to provide a movable lower section of skirting which is so arranged and operated as to permit the lower side wall chord to be carried directly past the step well thus obviating the use of heavy braces extended to the center sill.

A further object of the invention is the provision of a movable skirting which may be lowered away from the side door through an opening in the lower rigid step tread.

A still further object of the invention is the provision of a movable skirting which is shifted in unison with the trap door in order to clear the step well.

A yet further object of the invention is the provision of a movable skirting which may be retracted from a position in alignment with the car side wall in order to clear a rigid part of the car structure and then lowered to a supporting position where a portion thereof forms at least a part of a step tread.

These and other objects of the invention will be apparent to persons skilled in the art from a study of the following description and accompanying drawings in which:

Figure 1 is a broken sectional view taken through the step well with the retractable skirt in line with the car wall and trap door closed;

Fig. 2 is a broken horizontal sectional view taken through the step well with parts in the position shown in Figure 1;

Fig. 3 is a sectional view taken substantially on line 3—3 of Figure 1;

Fig. 4 is a broken sectional view similar to Figure 1 but showing the skirting lowered and the trap door raised in order to clear the step well for use;

Fig. 5 is a sectional view taken substantially on line 5—5 of Fig. 4;

Fig. 6 is an elevational view of the retractable skirting section as viewed from inside the step well, and

Fig. 7 is a detail view showing a slight modification in the linkage connecting the trap door and skirting.

Referring now to the drawings in detail, it will be seen that the invention has been shown as applied to a railway car having curved side walls 2 suitably braced by side posts 4 which are connected at their lower ends to a flanged channel sill 6 forming the lower chord of the side wall. Since the floor level is substantially above the side sill and the car is intended for use without platforms, it is necessary that the side sills be terminated at the step wells necessitating the carrying of the side wall loads past the step well. This is accomplished in the present instance by rigidly securing a structural member 8 of Z or other form to the side sills, which member is deflected downwardly from the sill and across the 10 step well, thus in effect continuing the lower chord directly past the step well (Figs. 1 and 4).

The step well itself is formed by transversely extending plates 10 rigidly secured to the side walls by angular shaped members 12 inwardly 20 of the edges of the door opening and these plates and edges of the door opening are connected together and braced by means of W section door posts 14 which in effect produce box section posts having opposed flanges defining the door opening and providing ledges 16 against which the side door may seal. The transverse plates 10 have step treads 18 and risers 20 securely attached thereto by any suitable means and are braced at their lower edges by angle member 22 30 secured to the lower chord 8 and to the center sill. The bottom or lowermost tread in the step well is preferably formed of a plurality of plates 18, as shown in Fig. 5, arranged to provide an opening for a purpose hereinafter set forth. The outer edge of one of the plates rests upon a pressed angle form member having one leg 24 thereof directed outwardly beyond the edge of the tread, while the other piece of tread rests upon and is secured to the chord member 8, the latter being additionally braced at the step well by an angle member having one leg 26 thereof extended inwardly beyond the edge of the tread part, thus providing, together with the leg 24, ledges upon which a removable section of tread (later to be 35 described) may be supported.

The major portion of the door opening will be closed by a suitably formed door having its outer surface 28 conforming to and substantially in alignment with the side wall of the car, while the inner or finish plate 30 is spaced sufficiently therefrom to provide a rigid door within which the usual latching mechanism (not shown) may be enclosed as well as a vertically sliding bolt 32. The upper end of this sliding bolt is provided 50 55

with an operating knob 34 extending through the finish plate, while the lower end extends through the lower door stiffener 36 in order that it may engage the retractable skirting.

5 The movable or retractable skirting member extends between the lower edge of the side door and the lower chord of the car structure and completely closes the opening to the step well appearing below the side door. This movable skirting is formed with an outer member 38 curved to conform to and be normally held in alignment with the car side wall skirting. To accomplish this the outer plate is deflected inwardly along its side edges as at 40, thus providing an offset flange 42 adapted to seat against resilient sealing means 44 (Fig. 2). The offset flanges 42 are connected by an inner finish plate 46, thus forming a rigid lower skirting section to the upper edge of which is attached on the inner side pan like pressings 48 adapted to rigidly support a section of tread plate 50 which is movable with the retractable skirt. This movable section of tread plate has its inner edge supported upon angle member 52 connecting the pan shaped pressings, while its outer edge is supported upon an outwardly directed flange 54 formed on the upper edge of the movable skirting and is adapted to engage with and seal against a downwardly and outwardly directed flange 56 formed on the lower edge of the side door. In order that the movable skirting may be operated a pair of triangular shaped pressings 58 are secured to the lower side edges thereof and to which the outer portion of a rigid operating arm 60 may be rigidly secured. The rigid operating arms are formed with a substantially flat surface 61 on their lower face which merges into a downwardly and outwardly curved surface 62 which in turn merges into an outwardly directed curved surface 63 terminating at a rounded point 64 formed between surfaces 63 and an upwardly curved surface 66 formed therebelow. The inner end of the curved surface 66 merges into a reversely curved surface 67 which in turn merges into the flat surface 68 forming the shank portion of the operating arm. It is thus seen that each rigid operating arm is provided on its lower side with a plurality of curved and straight cam surfaces, certain of which cam surfaces are adapted to engage upper and lower spaced rollers 70 and 71 carried by a casting 72 rigidly secured to the lower chord member 8 at the sides of the step well. In order to operate the movable skirting the inner end of each rigid operating arm is pivotally connected as at 73 to bellcrank lever 74 keyed or otherwise secured to a transverse shaft 75 journaled as at 76 in the side plates of the step well. One end of the transverse shaft is extended beyond its journal bearing for a rigid connection to bell crank arm 77 pivotally connected at one end to a thrust rod 78, the other end of which is pivotally connected to a thrust arm 79 rigidly secured to a pipe or other means 80 forming the customary pivot mounting for trap door 81 pivotally carried by one of the plates forming the step well side. As clearly shown in Figs. 2 and 3 the thrust arm 79 extends through the step well side plate, thus causing a downward movement of the thrust rod 78 when the trap door is lifted.

The operation of the mechanism is as follows and assuming the parts to be in their running position, namely, that shown in Figs. 1, 2 and 3: When it is desired to clear the step well for use of passengers, sliding bolt 32 will be lifted re-

leasing the movable skirting, after which the trap door will be unlocked and lifted in exactly the same way as is now done. During lifting of the trap door arm 79 will move downwardly causing thrust rod 78 to move downwardly and in turn rotating bellcranks 77 and 74 downwardly, thus causing the pivotal connection 73 to move downwardly on an arc a predetermined amount dependent upon the relative lengths of the various bellcrank levers. The downward movement of the pivotal connection 73 will also be accompanied with an inward movement since the bellcrank arm 74 is pivoted to the car structure above the pivotal connection and toward the center of the car. At the start of the downward and inward movement of pivotal connection 73 the operating arm 60 will act as a lever causing the upper portion of the movable skirt to tilt inwardly slightly away from the side door, also causing the flat portion 61 to assume a slightly inclined position instead of the horizontal position shown in Figure 1. At the same time that the movable skirt is tilting it will also be moving downwardly and inwardly under control of the rollers 70 and 71. While the pivotal connection 73 is moving downwardly and inwardly the roller 71 will move first along reversely curved surface 67, then along the upwardly curved surface 66 until such time as the rounded tip 64 is about to move off the roller 71. As soon as the tip 64 starts to move off the top of the roller 71, the end of the flat surface 61 is also ready to move off the roller 70 (line and dash position Fig. 4). Continued movement of the pivotal connection 73 causes the outer surface of flange 42 of the skirt to roll along rollers 70 and 71 until such time as the trap door is fully raised and the angle 52 and flange 54 of the movable skirt have engaged the legs 24 and 26 respectively of the angles adjacent the opening in the lower tread plate (full line position Fig. 4). In this final position it is seen that the movable tread plate 50 is rigidly supported upon the angles and forms a continuation of the rigid lower tread plate. With the parts in this position the side door may be swung inwardly overlapping the step well side wall and passengers may freely enter or leave the vehicle. In closing the step well the side door will first be closed, after which the trap door will be lowered and during its lowering will through the linkage cause an upward and outward thrust to be applied at the pivotal connection 73. This upward and outward thrust will cause the movable skirt to first roll along roller 70 then rollers 79 and 71 together until such time as upwardly curved surface 66 and flat portion 61 assume control. As soon as these portions have assumed control the skirt will move substantially laterally of the vehicle, while at the same time tilting slightly until it has assumed its operative position, after which bolt 32 may be slid downwardly locking the door and skirt together. It is evident from the above description and drawings that the center of gravity of the movable skirt assembly is at a considerable distance outward from the pivotal connection 73 and accordingly the assembly tends to rotate outwardly but is prevented by the rollers 70 and 71 which cooperate with the cam surfaces of the skirt and operating arm to control the movements of the assembly.

Ordinarily the weight of the movable skirt assembly is sufficient to insure proper movements thereof, but in case an extremely light construction is used it may be advisable to extend the rigid operating arm beyond the pivotal connec-

tion as at 90 and secure one end of a spring 92 thereto with the other end secured to a lug or other means 94 formed on bellcrank lever 14 (see Fig. 7). The remainder of the structure remains substantially the same and it is evident that this spring 92 will assist the gravitational thrusts thus insuring contact between the cam surfaces of the movable skirt assembly and the controlling rollers on the car structure.

10 It is evident from the preceding description that the movable skirt is moved inwardly or retracted from the car side wall during the first part of its movement, after which it is lowered to the final position in which a part thereof, namely, the tread surface, forms a part of the lower tread of the steps. It will be evident that the movable tread portion 50 may be increased or decreased within reasonable limits to form any desired portion of the lower step tread and it will 15 also be evident that the form of the cam surfaces on the rigid operating arm may be changed to cause slightly differing movements of the movable skirt assembly.

20 While the invention has been described more or less in detail, it is obvious that various modifications and rearrangements of parts, other than those mentioned above, will be apparent to persons skilled in the art and all such modifications and rearrangements of parts are contemplated as fall within the scope of the following claims.

30 What is claimed is:

1. In a vehicle, a body having a side wall, a side door in said side wall, a floor for said body having a cutaway portion opposite said door, a plurality 35 of steps secured to the body in the cutaway portion to provide a flight of steps leading downward from the floor to a lower step having a fixed tread section and a removable tread section, said fixed tread section having an opening therein adapted to receive the removable tread section to complete the tread, and means to raise said removable tread section to an inoperative position in spaced 40 relation to the fixed tread, said removable tread section forming in part closure means for the wall opening beneath said door.

45 2. In a vehicle, a body having a side wall, a side door in said side wall, a floor for said body having a cutaway portion opposite said door, a plurality 50 of steps secured to the body in the cutaway portion to provide a flight of steps leading downward from the floor to a lower step having a fixed tread section and a removable tread section, said fixed tread section having an opening therein adapted to receive the removable tread section to complete the tread, said removable tread section being secured to a movable portion of the side wall adapted to close the wall 55 opening beneath the side door, and means connected to said movable portion of the side wall and removable tread section to move the latter to an inoperative position in spaced relation to the fixed tread section and to move the former substantially into alignment with the side wall.

60 3. In a vehicle, a body having a side wall, a side door in said side wall, a floor for said body having a cutaway portion opposite said side door, a trap door adapted when closed to cover the cutaway portion and to lie substantially flush with the floor, a plurality of steps secured to the body in the cutaway portion thereby providing a flight of steps leading downward from the floor to a lower 65 step having a fixed tread section and a removable tread section, said fixed tread section having an opening therein adapted to receive the removable tread section to complete the tread, and means 70

connecting said removable tread section and trap door together for movement in unison, said removable tread section forming in part closure means for the wall opening beneath said door.

75 4. In a vehicle, a body having a side wall, a side door in said side wall, a floor for said body having a cutaway portion opposite said side door, a trap door adapted when closed to cover the cutaway portion and to lie substantially flush with the floor, a plurality of steps secured to the body 10 in the cutaway portion thereby providing a flight of steps leading downward from the floor to a lower step having a fixed tread section and a removable tread section, said fixed tread section having an opening therein adapted to receive the removable tread section to complete the tread, and means connecting said removable tread section and trap door together for movement in unison, said removable tread section forming in part closure means for the wall opening beneath said 15 door, said means being so constructed and arranged as to cause lowering of the removable tread section to an operative position substantially in alignment with the fixed tread section during raising of the trap door to an inoperative 20 position.

25 5. In a vehicle, a body having a side wall, a side door in said side wall, a floor for said body having a cutaway portion opposite said side door, a trap door adapted when closed to cover the cutaway portion and to lie substantially flush with the floor, a plurality of steps secured to the body 30 in the cutaway portion thereby providing a flight of steps leading downward from the floor to a lower step having a fixed tread section and a removable tread section, said fixed tread section having an opening therein adapted to receive the removable tread section to complete the tread, said removable tread being secured to a movable portion of the side wall adapted to close the wall 35 opening beneath the side door, and means connecting said movable wall portion and removable tread section to the trap door for movement in unison but in opposite directions.

40 6. In a vehicle, a body having a floor with a cutaway portion intermediate the ends thereof, a side wall having an opening therein at the cutaway floor portion and having a side door closing at least the upper portion of the opening, said side wall being constructed with a lower chord extending substantially continuously from end to end thereof and across the wall opening, a plurality of steps secured to the body in the cutaway portion thereby providing a flight of steps leading downward from the floor to a lower step tread, said lower step having a fixed tread section secured to the lower chord in the wall opening and a removable tread section, said fixed tread section having an opening therein inward of the lower chord adapted to receive the removable tread section to complete the tread, and means to raise 45 the removable tread section to an inoperative position in spaced relation to the fixed tread, said removable tread section forming in part closure means for the wall opening beneath said door.

50 7. In a vehicle, a body having a floor with a cutaway portion intermediate the ends thereof, a side wall having an opening therein at the cutaway floor portion and having a side door closing 55 at least the upper portion of the opening, said side wall being constructed with a lower chord extending substantially continuously from end to end thereof and across the wall opening, a plurality of steps secured to the body in the cutaway 60

- portion thereby providing a flight of steps leading downward from the floor to a lower step tread, said lower step having a fixed tread section secured to the lower chord in the wall opening and 5 a removable tread section, said fixed tread section having an opening therein inward of the lower chord adapted to receive the removable tread section to complete the tread, said removable tread section being secured to a movable portion 10 of the side wall to form a unit adapted to close the wall opening beneath the side door, and means connected to said unit so constructed and arranged as to move the unit past the lower chord and portions thereof into substantial alignment 15 with either the side wall or fixed tread section.
8. In a vehicle, a body having a floor with a cutaway portion intermediate the ends thereof, a side wall having an opening therein at the cutaway floor portion and having a side door closing 20 at least the upper portion of the opening, said side wall being constructed with a lower chord extending substantially continuously from end to end thereof and across the wall opening, a plurality of steps secured to the body in the cutaway portion thereby providing a flight of steps leading downward from the floor to a lower step tread, said lower step having a fixed tread section secured to the lower chord in the wall opening and 25 a removable tread section, said fixed tread section having an opening therein inward of the lower chord adapted to receive the removable tread section to complete the tread, a trap door hinged to the body and adapted when closed to cover the flight of steps and to lie substantially flush with the floor, and means connecting the trap door and removable tread section, said removable tread section forming in part closure means for the wall opening beneath said door, 30 said means being so constructed and arranged as to cause lateral inward movement of the removable tread section prior to lowering thereof in order to clear the lower chord during the raising of the trap door to an inoperative position. 35
11. In a vehicle, a body having a floor with a cutaway portion intermediate the ends thereof, a side wall having an opening therein at the cutaway floor portion and having a side door closing at least the upper portion of the opening, said side wall being constructed with a lower chord extending substantially continuously from end to end thereof and across the wall opening, a plurality of steps secured to the body in the cutaway portion thereby providing a flight of steps leading downward from the floor to a lower step tread, said lower step having a fixed tread section secured to the lower chord in the wall opening and 40 a removable tread section, said fixed tread section having an opening therein inward of the lower chord adapted to receive the removable tread section to complete the tread, said removable tread section being secured to a movable portion of the side wall to form a unit adapted to close the wall opening beneath the side door and above the lower chord, a trap door hinged to the body and adapted when closed to cover the flight of steps, and means connecting the trap door and unit for movement in unison, said means being so constructed and arranged as to cause movement of the unit laterally inward to clear the lower chord prior to the lowering of the unit, said movement being accomplished during the raising of the trap door to an inoperative position thereby placing the flight of steps in condition for use. 45
12. In a vehicle, a body having a floor with a cutaway portion intermediate the ends thereof, a side wall having an opening therein at the cutaway floor portion and having a side door closing at least the upper portion of the opening, said side wall being constructed with a lower chord extending substantially continuously from end to end thereof and across the wall opening adjacent the lower edge of the opening, a plurality of steps secured to the body in the cutaway portion with the lower step tread secured to the top chord, said lower tread being formed of relatively fixed plates with an opening therein to receive a removable plate, said removable plate being secured to a removable wall section adapted to close the opening between the lower step tread and side door, said removable wall section normally positioned substantially in the plane of the side wall with the removable tread plate in spaced relation to the fixed tread plate, and means connected to the removable wall 50
- 78

- section to cause lateral inward movement of the same prior to the lowering thereof through the opening in the fixed tread plate, said means finally positioning the removable tread plate substantially in alignment with the fixed tread plate with the removable wall section projecting therebelow.
13. In a vehicle, a body having a side wall with an opening therein, a floor positioned above the lower edge of the side wall, a plurality of steps secured to the body and extending from the floor substantially to the lower edge of the side wall at the opening, a side door closing at least the upper portion of the opening, a lower chord secured to the side wall and extending substantially from end to end of the car and across the said opening beneath the lowermost step, a removable wall section normally located in an in-use position substantially in alignment with the side wall for closing the remainder of the opening between the side door and lower chord, and means connected to the removable wall section to move the same to an out-of-use position inward of and below the lower chord.
14. In a vehicle, a body having a side wall with an opening therein, a floor positioned above the lower edge of the side wall, a plurality of steps secured to the body and extending from the floor to a lower step substantially at the lower edge of the side wall adjacent the opening, a side door closing the upper portion of the opening, a lower chord secured to the side wall and extending substantially from end to end of the car and across the said opening beneath the lower step, a removable wall section normally located in an in-use position substantially in alignment with the side wall for closing the remainder of the opening between the side door and lower chord and blocking access to the steps from the exterior of the vehicle, a trap door normally located in an in-use position substantially in alignment with the floor for blocking access to the steps from the vehicle interior, and means interconnecting the trap door and removable wall section whereby the latter is moved to an out-of-use position inward of and below the lower chord during raising of the trap door to out-of-use position thereby clearing the steps for use.
15. In a vehicle, a body having a side wall with an opening therein, a floor positioned above the lower edge of the side wall, a plurality of steps secured to the body and extending from the floor to a lower step substantially at the lower edge of the side wall adjacent the opening, a side door closing the upper portion of the opening, a lower chord secured to the side wall and extending substantially from end to end of the car and across the said opening beneath the lower step, a removable wall section normally located in an in-use position substantially in alignment with the side wall for closing the remainder of the opening between the side door and lower chord and blocking access to the steps from the exterior of the vehicle, a trap door normally located in an in-use position substantially in alignment with the floor for blocking access to the steps from the vehicle interior, and means interconnecting the trap door and removable wall section whereby the latter is moved to an out-of-use position inward of and below the lower chord during raising of the trap door to out-of-use position thereby clearing the steps for use.
16. In a vehicle, a body having a side wall with an opening therein, a floor positioned above the lower edge of the side wall, a plurality of steps secured to the body and extending from the floor to a lower step substantially at the lower edge of the side wall adjacent the opening, a side door closing the upper portion of the opening, a lower chord secured to the side wall and extending substantially from end to end of the car and across the said opening beneath the lower step, a removable wall section normally located in an in-use position substantially in alignment with the side wall for closing the remainder of the opening between the side door and lower chord and blocking access to the steps from the exterior of the vehicle, a trap door normally located in an in-use position substantially in alignment with the floor for blocking access to the steps from the vehicle interior, and means interconnecting the trap door and removable wall section whereby the latter is moved to an out-of-use position inward of the lower chord during raising of the trap door to out-of-use position thereby clearing the steps for use, said means including a plurality of cam surfaces cooperating with body carried cam elements whereby the removable wall section is moved laterally inward from the side wall and then lowered through an opening in the lower step.
17. In a vehicle, a body having a side wall with an opening therein, a floor positioned above the lower edge of the side wall, a plurality of steps secured to the body and extending from the floor to a lower step substantially at the lower edge of the side wall adjacent the opening, a side door closing the upper portion of the opening, a lower chord secured to the side wall and extending substantially from end to end of the car and across the side opening beneath the lower step, a removable wall section normally located in an in-use position substantially in alignment with the side wall for closing the remainder of the opening between the side door and lower chord and blocking access to the steps from the exterior of the vehicle, a trap door normally located in an in-use position substantially in alignment with the floor for blocking access to the steps from the vehicle interior, and means interconnecting the trap door and removable wall section whereby the latter is moved to an out-of-use position inward of the lower chord during raising of the trap door to out-of-use position thereby clearing the steps for use, said means including a plurality of cam surfaces cooperating with body carried cam elements whereby the removable wall section is moved laterally inward from the side wall and then lowered through an opening in the lower step.
18. In a vehicle, a body having a side wall, a side door in said side wall, a step well, a flight of steps secured to the body in said step well and having a lower step positioned below and in spaced relation to said door, retractable closure means for closing the side of the step well below said door, said lower step having an opening therein, a removable tread section secured to and forming part of said closure means and adapted to be received in said opening to complete said lower step, and means for moving said closure means substantially into alignment with said side wall to close the step well, said removable tread section being so formed and arranged as

to provide a sealing element between said closure means and side door.

19. In a vehicle, a body having a side wall, a side door in said side wall, a step well, a flight of steps secured to the body in said step well and having a lower step positioned below and in spaced relation to said door, said lower step having a fixed tread section and a removable tread section, said removable tread section being secured to retractable closure means for closing

the side of the step well below said door, and means for moving said retractable means and removable tread section, said removable tread section being adapted when in one position to form a seal between the retractable closure means and said door and in another position to engage said fixed tread section and cooperate therewith to complete said lower step.

SIGVALD F. UDSTAD. 10
